UNITED STATES PATENT OFFICE.

EWEN A. CLARK, OF REVERE, MASSACHUSETTS.

TORPEDO-NET.

1,240,317.

Specification of Letters Patent. Patented Sept. 18, 1917.

Application filed December 15, 1914. Serial No. 877,445.

To all whom it may concern:

Be it known that I, EWEN A. CLARK, a citizen of the United States, and a resident of Revere, in the county of Suffolk and 5 Commonwealth of Massachusetts, have invented certain new and useful Improvements in Torpedo-Nets, of which the following is a full, clear, and exact specification.

10 Many warships are provided with nets suspended about them for the purpose of entangling and stopping any torpedoes which may be launched against them. The difficulty with such nets is, however, that in the 15 case of the modern high-speed torpedo, they prove unable to stay the progress of the same, and the torpedo passes through the nets into engagement with the warship.

The purpose of this invention is the effecting of improved means for preventing such penetration of the nets. To this end, 20 my invention consists in providing each mesh of the net with a resiliently tightening slip-noose adapted to be entered by a torpedo striking such point, and to give such a frictional retardation to the progress of the missile as to cause it to be brought to a stop before its nose can meet the ship's side.

Referring to the drawings forming part 30 of this specification, Figure 1 is a face view of a section of a guard net provided with my improvements. Fig. 2 is a perspective view of one of the resilient nooses alone. Fig. 3 is a side view of a torpedo penetrating 35 a net and engaged by a noose. Fig. 4 is a detail view of one of the noose-holding clips. Fig. 5 is a diagram illustrating several ships towing booms carrying my improved netting. Fig. 6 is an elevation of a 40 section of a boom having the netting suspended therefrom. Fig. 7 is a cross section of a boom and netting supported thereby. Fig. 8 is a cross section of a boom having 45 the netting partially wound thereon. Fig. 9 is a cross section of a boom provided with a turning rope.

Although I do not illustrate a war ship, nor the net-supporting arms usually employed for the suspension of the protecting 50 netting, yet I show a means for supporting the same, which comprises a floating boom, and a portion of the net provided with my resilient noose in its set and gripping conditions.

55 Looking first at Fig. 1, the net is illustrated as composed of vertical ropes 1 and

horizontal ropes 2 fastened together at their intersections, and uniformly spaced, the ropes being preferably about eighteen inches apart. While ropes are thus shown, I do 60 not restrict myself thereto, as chains, rods and the like may be used for such reticulated members.

Within each mesh of the portion of the net normally beneath the water, and closely positioned beside the vertical and horizontal members 1, 2, is a slip noose formed of powerful rope of wire or fiber, said rope 3 having one end strongly fastened to a ring 4 65 slideable on the body of the rope. The other 70 end of the rope 3 is suitably attached to the net, preferably to the lower horizontal member 2 about midway of the adjacent mesh, as at 5.

Upon the portion of the rope 3 between 75 the ring 4 and the fastening 5, is a strong helical spring 6 of the open type and hence fitted for expansion. As illustrated in Fig. 1, this spring is compressed to its limit, and if released would quadruple in length. 80

To keep the spring 6 compressed and the loop widely open, and so in a condition to receive a torpedo, a catch 7 is fixed in each corner of the mesh for the reception of the loop, said catch being preferably a spring 85 clip adapted to grip the rope 3 with sufficient strength to insure against the loop's being dislodged by the waves, but not enough to hold it against the tripping devices employed. The tripping devices preferably comprise a wire 10 passed about the loop within the clips, so that when said wire 90 is strongly pulled inward it will draw the loop out from the clips and permit it to be drawn about the torpedo penetrating it. 95

The means for thus pulling upon the wire 10 consists of a pair of diametrically disposed wires 12 terminally attached to the wire 10, said wires or ropes 12 being fastened together at their intersection. When 100 the nose of a torpedo shoots into any one of the four spaces inclosed by the wires 10 and 12, it gives such a pull thereon as instantly to jerk loose both the wires and the loop 3 entirely free of the clips 7, and so 105 drops the loop upon the torpedo.

One of said clips 7, preferably the one at the lower right hand corner of each mesh, is positioned in a plane parallel with the ropes 1 and hence adapted to have the ring 110 4 pressed against it by the helical spring 6, and to hold the latter in its compressed

condition. Consequently, the instant the pull upon the wire net 10, 12 has withdrawn the rope or loop 3 from all the clips 7, said spring is no longer held back but 5 forces the ring 4 along the rope 3 until the loop has been drawn tightly about the torpedo.

This spring 6 being made quite powerful, it gives to the loop such a tight grip upon 10 the torpedo as to form in effect a friction brake upon the latter's progress, so that even if it has not fully brought the torpedo to rest before the loop has been left behind, yet the loop will engage the propeller 15 and by that means stop further advance of the torpedo.

Further, since the torpedo is held back by a pull at one side thereof, as shown in Fig. 3, the steady drag thereon will cause 20 the torpedo to swing about until it is substantially parallel with the net and hence incapable of reaching the ship's side even if the slip noose should fail to stop it entirely. Should the torpedo have been provided with a time-fuse, instead of a 25 percussion head, it would thus be held so far from the ship as to be incapable of harming the latter when the explosion occurs.

As illustrated in Fig. 4, the clips 7 are 30 not parallel with the ropes 2, but are deflected inward therefrom at an angle of approximately forty-five degrees, in order that the pull toward the ship given by a torpedo to the net 10, 12 will act to withdraw 35 the wires and rope 3 from the clips.

While this netting may be suspended from arms projecting from the warships, I prefer to attach it to a boom 16, as shown in Figs. 6 and 7. A series of these netting-carrying booms being trailed behind a war 40 vessel, as 17, in Fig. 5, a second war vessel somewhat behind and to one side of the boom will be protected by the netting on the boom; and the second vessel 18 being 45 made to trail another series of booms 16 behind it, a third vessel 19 will be similarly protected, and so on for any desired length of fleet.

When the booms are to be stowed away on 50 deck or elsewhere, the netting is rolled up thereon, as partially shown in Fig. 8; and to do this readily, I prefer to coil a rope 21 upon the boom, as shown in Figs. 6 and 9, so that by pulling upward on said rope, 55 the boom is rotated in a direction to wind the netting thereon. By pulling the rope 22, which is wound in the opposite direction, the boom is turned to unwind and let down the netting.

Although I have described this net as 60 designed for the capture of torpedoes, it is evident that it can be also employed for catching large fish.

Further, by making the netting sufficiently large and strong, and the loops of

powerful cables or chains, the same can be used for entangling submarines.

In addition to the protection of war ships, the booms carrying the netting and entangling loops can be fixed across the mouth 70 of harbor or river for the purpose of securing the same against the admission of submarines, torpedoes and the like. Hard projections 20 may be made in the loop to increase its grip. 75

What I claim is:

1. The combination with a netting comprising ropes or the like secured together at their intersections, of a slip noose supported in each mesh of the netting with one 80 end attached to the netting.

2. The combination with a netting, of a slip noose supported in each mesh of the netting and having one end attached to the netting, each slip noose being supported to 85 closely coincide with the sides of the mesh containing it.

3. The combination with a netting comprising ropes secured together at their intersections, of a slip noose supported in each 90 mesh of the netting and having one end attached to the netting, resilient means for tightening each slip noose, and means temporarily holding said means from acting upon each noose. 95

4. The combination with a netting having meshes of a material size, of a slip noose supported in each mesh of the netting and attached to the netting, resilient means for tightening each noose, and easily releasable 100 means holding said tightening means inactive.

5. The combination with a netting having meshes of a material size, of a slip noose supported in each mesh of the netting and 105 attached at one end thereto, a helical spring mounted on each noose between its attached end and the movable end thereof, means for holding said springs compressed, and means for releasing said springs. 110

6. A rope or the like having one end anchored and the other formed into a slip noose, in combination with a helical spring mounted upon the rope between the anchored end and the noose, and easily released means for holding the spring compressed. 115

7. The combination of a netting comprising spaced horizontal and vertical members, clips at the intersections of said members, a section of netting held in said clips, a rope having one end attached to the first-named netting and its other end formed into a slip noose, the latter being held in said clips, and a helical spring mounted on 120 the rope between the attached end and the nearest clip, the section of netting being disposed in said clips to pull the loop out from the clips when said section is drawn out therefrom. 130

8. The combination with a netting, of a loop fastened in each of certain openings therein, each loop being constructed to resiliently resist expansion and being fastened to one side of the opening, whereby a torpedo penetrating one of the loops will be given a resistance to further progress eccentric to its longitudinal line.

In testimony that I claim the foregoing invention, I have hereunto set my hand this 14th day of December, 1914.

EWEN A. CLARK.
